UNITED STATES PATENT OFFICE

FRANK E. EWELL, OF EAST BRIDGEWATER, MASSACHUSETTS, ASSIGNOR TO UNITED SHOE MACHINERY CORPORATION, OF PATERSON, NEW JERSEY, A CORPORATION OF NEW JERSEY

FASTENING-INSERTING MECHANISM

Application filed September 17, 1926. Serial No. 136,051.

My invention relates to mechanisms by which fasteners are inserted for securing to one another such work-portions as parts of shoes, it being herein disclosed as applied to 5 the nail-driving mechanism of a heel-attaching machine.

In the heelng of shoes it is customary to hold the heel to be attached against a die-block in which, opposite the positioned heel, 10 are nail-receiving openings, and to press against this heel the heel-seat of a jacked shoe, drivers thereafter reciprocating in the die-block to effect the insertion of the nails which secure the heel to the shoe. Since heels vary 15 widely in their horizontal dimensions, and since it is desired to keep the nails as close to the periphery as possible to obtain a tight rand-crease, the nailng-designs differ considerably in the area occupied. The breast-nail 20 openings of the larger designs may approach closely to the forward edge of the die-block, while the corresponding openings for the smaller will be spaced a substantial distance from the edge. With the latter of these 25 nailings, it is found that for some shoes, especially those having a high arched shank which slopes down sharply to the tread, the edge of the die-block may contact with the outsole at the shank, and when pressure is applied to the work, preliminary to driving the 30 nails, an indentation is produced which defaces the outsole. To prevent this, the expedient of beveling the die-block has been resorted to, so the shank remains clear of the edge. 35 This is satisfactory for small heels but, for those which are large, there tends to be an undue removal of the abutment-surface receiving the pressure opposing the nailng force, the bevel sometimes cutting back into the 40 breast-openings of the larger nailings. Under such conditions these outer or breast-nails may not be clinched properly and the desired tight joint between the heel and heel-seat is not obtained. It therefore may become necessary 45 to use a plurality of die-blocks, which involves considerable expense and is, of course, troublesome, as the blocks are heavy. It is an object of the present invention to provide a nailng mechanism in which an efficient 50 abutment surface will be afforded for heels

of all sizes. This I accomplish by means of a die-block or other abutment member, with the fastening-receiving openings of which driving members co-operate, said die-block having a portion so movable as to vary the work-engaging surface. In a nailng mechanism, as one by which heels are attached, the lower edge of the die-block, in accordance with my invention, contains a depression adjacent to the nail-receiving openings. In this 55 depression a sliding member is mounted to move between a point opposite the openings, at which it gives an abutment surface of a dimension such as to effectively resist the pressure of the largest heel to be nailed, and 60 a point on one side of the openings, this affording a space which the shank-portion of a small-heel shoe may occupy without danger of contact with the block. Preferably the 65 sliding member is divided, there being portions movable in the depression toward and from each other.

In the accompanying drawing a particular embodiment of my invention is illustrated,

Fig. 1 showing in perspective the nailng mechanism of a heel-attaching machine, the die-block of said mechanism being arranged in accordance with this invention;

Fig. 2 is a broken perspective view of the under-side of the die-block, and

Fig. 3 is a partial section on the line III—III of Fig. 1.

For a general disclosure of the type of heelng machine, a portion of which I have chosen to illustrate, reference may be had to 85 United States Letters Patent No. 446,885, Pope, February 24, 1901. Of this appears a frame 10 supporting a horizontal die-block 12 in which are nail-receiving openings 14. As is usually the case, these openings may include a multiple of all of the nailng designs which are to be employed, two designs being completely shown and designated as *a* and *b*, these being respectively for the largest and smallest heels to be nailed.

Guided in the frame are vertically reciprocating side rods 16, one only of these appearing in the drawing, said rods carrying upon their upper extremities a top girt 18. Mounted upon the die-block at the center of 100

the top girt is a plate 20 from which depend multiple drivers 22, there being one alined with each of the die-block-openings. The travel of these drivers, under the influence of the side rods, causes them to act upon the 5 nails which have been placed in the die-block openings to drive them into the work.

At 24 appears the upper portion of a jack, this carrying a shoe S, the heel-seat of which is forced against a heel (not shown), and this, in turn, against the die-block opposite the openings in which are the attaching nails. In the present instance, the heel to be attached is of such size as to call for the use of the 10 smallest nailing design, so the nails will be loaded into the openings b.

The forward lower edge of the die-block is recessed, there being a depression 26 rectangular in transverse section extending between the opposite ends. In the upper wall 20 of this depression ways are formed, shown as furnished by a longitudinally extending dovetailed recess 28, which guides in the depression slides 30, 30 having dovetailed projections 32 entering the recess 28. The slides may be of such transverse dimensions as to 25 fill the depression and thus restore the abutment or pressure-receiving surface of the block to its full width. The slides have such an aggregate length that, when they are moved to the outer extremities of the depression, there will be left between their inner 30 ends a space sufficient to receive the widest shank-portion of a shoe having a small heel, for which it is desired to furnish a space at 35 the edge of the die-block opposite the nail-receiving openings 14. On the other hand, when the slides are brought together they complete the abutment surface adjacent to 40 the openings for the satisfactory nailing of the largest heel. In their relation the slides may be secured by set screws 34 threaded through them and bearing at their inner extremities against the wall of the depression.

45 In using the above described organization for nailing small heels in which the breast-nail-openings are substantially spaced from the front of the die-block, the slides 30 are fixed by the screws 34 at the outer extremities of the depression 26. There is thus formed a space into which the shank-portion 50 of the outsole may extend without contact with the block. Therefore, there will be no scoring of the shank when clamping pressure is applied to the work. When the heel-size 55 is such that the breast-nail-openings approach the front of the block, the slides are moved to a central position with their inner ends together. The block is, at the portion 60 co-operating with the shoe, thereby restored to its normal rectangular form in transverse section, presenting a surface for engagement with even the largest heel adjacent to the breast-nails. A firm holding of 65 this portion of the work is therefore assured,

with a perfect clinching of the breast-nails and a tight joint between the heel and heel-seat.

Having fully described my invention what I claim as new and desire to secure by Letters Patent of the United States is:

1. The combination with a movable driving member, of an abutment member against which work may be pressed to resist the driving force, said abutment member being provided with a portion movable thereon and arranged to vary the work-engaging surface.

2. The combination with a movable driving member, of an abutment member against which work may be pressed to resist the driving force, said abutment member being provided with a depression, and opposite members arranged to move toward and from each other in the depression.

3. In a nailing machine, nailing mechanism including a block provided with nail-receiving-openings, and a slide movable upon the edge of the block adjacent to the openings.

4. In a nailing machine, nailing mechanism including a block provided with nail-receiving-openings and with a depression along one edge and extending to opposite sides of the nail-receiving-openings, slides movable toward and from each other at 95 opposite ends of the depression, and a securing means for each slide.

5. In a heel-attaching machine, nail-driving mechanism including a die-block upon a front edge of which are ways, and a slide 100 movable upon the ways.

6. In a heel-attaching machine, reciprocating drivers, a die-block having openings to receive the drivers, a jack co-operating with the die-block and arranged to receive a 105 shoe to be heeled with its forepart extending beyond the die-block, there being a depression in said die-block adjacent to the shank-portion of the jacked shoe, a slide movable in the depression from a point opposite said 110 shoe to one side thereof, and a securing device for the slide.

In testimony whereof I have signed my name to this specification.
